UNITED STATES PATENT OFFICE

ARTHUR V. DA COSTA, OF PROVIDENCE, RHODE ISLAND.

TOY.

Application filed November 12, 1921. Serial No. 514,755.

To all whom it may concern:

Be it known that ARTHUR V. DA COSTA, a citizen of the United States, residing at Providence, in the county of Providence and State of Rhode Island, has invented certain new and useful Improvements in Toys, of which the following is a specification.

This invention relates to improvements in the construction of toys, and has for its object to provide a toy having a bulbous body with a head and limb members connected to the body member by an elastic cord whereby these limb members are universally yieldable relative to the body.

15 A further object of the invention is the provision of means within the bulbous members whereby a noise is made to serve as a rattle when the toy is agitated.

With these and other objects in view, the 20 invention consists of certain novel features of construction, as will be more fully described, and particularly pointed out in the appended claims.

In the accompanying drawings:

25 Figure 1 is a front view of my improved toy.

Figure 2 is a view of the toy in section showing its head and limbs as being connected to the body by an elastic cord.

30 Figure 3 is a section of the head-member and the body-member, showing the edges of one half of the sphere as fitting into those of the other half of the sphere.

It is found very desirable to produce a toy 35 in the form of an attractive doll having a body-member and a head-member and to flexibly and yieldably attach arms and legs to this body, and it is found of great advantage in such a toy to form the members 40 of the doll hollow so that it shall be very light in weight and so prevent injury to the child playing with the toy; also by making the top up of hollow members it is adapted to receive small pieces of loose material 45 to shake about when the toy is agitated to serve as a rattle, and the following is a detailed description of one means by which this result may be accomplished:

With reference to the drawings, 10 designates the hollow, bulbous body-member of the toy which may be in any suitable or desired shape such as egg-shape, spherical shape, or the like.

On the upper surface of this body member I have mounted a head member 9 and on the lower side of this body-member I have

mounted two radially-disposed legs, each being preferably formed of two or more spherically-shaped members 11 and 12 which are provided with oppositely-disposed holes 13.

In order to secure these legs and the head member to the body I have employed a piece of elastic cord 14 folded at its middle into two parts and knotted it as at 15 at the fold. These two parts are then passed down through an opening 16 in the top of the head-member, through an opening 17 in the lower part of the head-member, through an opening 18 in the top of the body-member, through openings 19 and 20 in the bottom of the body-member and each part passed through the opening 13 in its respective leg member. The cord is now stretched slightly and knotted as at 21 and 22 on the outside 75 of each of the outer leg-members whereby the tension on this elastic cord performs three functions; it secures the head to the top of the body and each of the legs to the bottom portion of the body whereby all are 80 flexibly or yieldably mounted upon the body and in addition the point between the leg members are also flexible whereby either of the legs serves as a convenient flexible handle by which the toy may be grasped and shaken about to agitate the loose material 85 therein to serve as a rattle.

In addition to attaching the legs to the body I also provide a pair of spherical arm members 23 which are secured to the body 90 by means of an elastic cord 24 which passes through the body and through the arm members being knotted as at 25 on the outer surface thereof. These knots on the arms are covered by a small cup-shaped member 26 95 while the knots on the legs are covered by similar members 27 and the knots on the outer surface of the head-member are covered by a hat member 28.

All of the members of which the toy is 100 constructed are preferably formed in halves, each half being pressed into the desired form, each member being constructed of any suitable sheet material preferably celluloid, the meeting edges 29 and 30 of these halves being designed to fit one with the other and be connected together preferably by cement.

By my improved construction a doll is formed extremely light in weight and all of the members are flexibly or yieldably mounted upon a body portion and in addition the legs are also flexible or yieldable at their 110

joints between the members of which they are constructed.

The device is extremely strong and durable in construction and handsome and attractive in appearance and serves as a very effective rattle.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

15. 1. A toy comprising a hollow bulbous body member having hollow bulbous head and limb members connected thereto by an elastic connector, all of said members having convex contacting surfaces whereby they are universally yieldable relatively to the body member and are held under yielding tension to roll one upon the other to automatically return to normal when displaced.

25. 2. A toy comprising a hollow bulbous body member having a head mounted thereon, arms each constructed of a plurality of bulbous members, each having convex contacting surfaces and connected together directly through said body by a continuous elastic cord under tension whereby said

members roll one upon the other to automatically return to normal after having been displaced.

3. A toy comprising a bulbous body having a head, a pair of legs each constructed of a plurality of bulbous members, and an elastic cord extending through the several members of each leg and through the body and head members flexibly connecting them all together, the ends of the cord being knotted on the outside of the members attached to the body, and a cap covering said knotted ends.

4. A toy comprising a hollow bulbous body having a head, legs each constructed of a plurality of hollow spherical members, and an elastic cord extending through the several members of each leg and through the body and head members flexibly connecting them all together to roll one upon the other and return to normal when displaced, a pair of arm members having convex contacting surfaces, and an elastic cord flexibly connecting said arms to said body, said cords being under tension to permit a relative rolling movement of said members to return the parts automatically to normal after having been displaced.

In testimony whereof I affix my signature.

ARTHUR V. DA COSTA.
